[57] CLAIM

The ornamental design for a paint can lid, as shown and described.

DESCRIPTION

FIG. 1 is a perspective view of a paint can lid showing my new design;

FIG. 2 is a top plan view thereof;

FIG. 3 is a side elevational view thereof;

FIG. 4 is a bottom plan view thereof;

FIG. 5 is a rear elevational view thereof; and,

FIG. 6 is a front elevational view thereof.

The broken-line showing of the paint can in FIG. 1 is for information only and forms no part of the instant design.

FIG. 1

FIG. 2

FIG. 3

FIG. 4

FIG. 5

FIG. 6
